UNITED STATES PATENT OFFICE.

JAMES H. HORNE, OF DAYTON, OHIO, ASSIGNOR TO THE BARNEY & SMITH CAR COMPANY, OF SAME PLACE.

DESIGN FOR A CEILING FOR CARS.

SPECIFICATION forming part of Design No. 32,033, dated December 26, 1899.

Application filed September 14, 1899. Serial No. 730,507. Term of patent 7 years.

To all whom it may concern:

Be it known that I, JAMES H. HORNE, a citizen of the United States, residing at Dayton, in the county of Montgomery and State of Ohio, have invented and produced a new and original Design for a Ceiling for Cars, of which the following is a specification, reference being had to the accompanying drawings, forming part thereof.

10 Figure 1 of the drawings represents an inverted plan view, and Fig. 2 a perspective sectional view, of my new design for a car-ceiling.

15 The special or leading feature of my design consists of the peculiar configuration or shape for a ceiling for cars, the same being composed of a central elevated portion A and two lower portions B B, disposed or arranged as shown

in the drawings. The said portion A is substantially semicircular in form; and the said 20 portions B B are each curved to substantially the arc of a circle. The terminal edges F G of the said portions A and B B are joined together by strips H H.

Having described my invention, what I 25 claim as new, and desire to secure by Letters Patent, is—

The design for a ceiling for cars as herein described and shown.

In testimony whereof I hereunto subscribe 30 my name and affix my seal this 12th day of September, 1899.

JAMES H. HORNE. [L. S.]
In presence of—
N. EMMONS, Jr.,
E. B. LEHMAN.
